UNITED STATES PATENT OFFICE

2,250,500

ABRADING APPARATUS

William A. Rosenberger, Hagerstown, Md., assignor to Pangborn Corporation, Hagerstown, Md., a corporation of Maryland

Application September 21, 1937, Serial No. 164,924

7 Claims.

(Cl. 51—9)

The present invention relates to abrading and cleaning apparatus and methods and more particularly to methods of, and apparatus for, subjecting articles uniformly to abrading or cleaning blast streams at successive blasting stations, as shown in my application Serial No. 34,990, filed August 6, 1935.

In the copending application of Eric O. Hamren, Serial No. 65,509, filed February 24, 1936, now Patent No. 2,160,697, dated May 30, 1939, is disclosed an abrading apparatus in which an article or casting is continuously rotated and simultaneously subjected to abrading and cleaning blast streams at a single blasting station to which it has been moved and before which it has been stopped by a suitable intermittent drive mechanism.

The present invention provides a machine having a plurality of blasting stations before which the article or casting is stopped in successive operations and is designed to overcome certain problems in abrading and cleaning to be later brought forth.

It is a primary object of the present invention to provide a novel apparatus for abrading and cleaning all portions of an article uniformly and thoroughly by subjecting the article to abrading or cleaning action at successive blasting stations.

A further object of my invention is to provide, adjacent a path along which articles or castings are guided, a novel arrangement of spaced blasting stations for directing blast streams at various angles upon each of the articles as it pauses before each blast station in succession.

It is a further object of my invention to provide a novel apparatus for moving an article through an abrading zone made up of a plurality of spaced blasting stations for directing blast streams at various angles upon the article and causing the article to dwell for a substantial measured length of time in the blast stream at each blasting station in succession whereby it is subjected to measured uniform abrading action.

A further object of my invention is to provide an abrading or cleaning apparatus having a plurality of spaced blasting stations for directing blast streams at various angles to a path along which a plurality of articles may be moved, the articles being subjected to abrading action at each of the blasting stations in succession and wherein a plurality of articles may be operated upon simultaneously by the blasting stations.

A further object of my invention is to provide a novel conveyor mechanism for use in an abrading apparatus for moving a continuously rotating

article past a plurality of separate blasting stations at various speeds.

A further object of my invention is to provide a novel work carrier for supporting work to be moved through a multiple station abrading zone.

A further object of my invention is to provide a novel adjustable reciprocating mechanism for intermittently moving a work carrier conveyor in one direction only along a closed path in an abrading apparatus.

A further object of my invention is to provide a novel mechanism for continuously rotating a work carrier while it is in an abrading zone.

Another important object of my invention is 15 to provide a novel method of abrading and cleaning articles, especially long castings, wherein each article is moved through an abrading zone made up of a plurality of spaced blasting stations and caused to dwell for a substantial length of time before each blasting station in succession whereby it is subjected to a plurality of different and independent abrading actions directed at various angles.

Another important object of my invention is 25 to provide a novel method of abrading and cleaning rotating articles wherein the articles are subjected to blast streams successively from spaced offset blasting stations to insure thorough cleaning action.

30 Other objects of the invention will be apparent from the following description and the appended claims taken in connection with the accompanying drawings wherein:

Figure 1 is a photographic view in elevation of 35 a complete apparatus embodying the invention showing the general operation of the apparatus in actual use and especially the vertical spacing of the several blasting stations.

Figure 2 is a right-hand end view partly in 40 section illustrating the arrangement of some of the blasting stations and the entry by which the work enters the abrading zone.

Figure 3 is a diagrammatic view illustrating 45 a preferred arrangement of the several blast wheels with respect to the casting or other work to be blasted.

Figure 4 is a diagrammatic top plan view of 50 the apparatus of the invention showing the closed path along which the work is guided and the spaced relation of the several blasting stations.

Figure 5 is a fragmentary partially diagrammatic plan view on a larger scale than Figure 4 and illustrating the various elements for operating upon the work carrier at the abrading zone.

Figure 6 is an enlarged sectional view showing the details of the work carrier guides and chain drive at the abrading zone.

Figure 7 is a diagrammatic end view partly in section of the abrasive propelling wheel used at each blasting station in the apparatus.

Figure 8 is a side view on an enlarged scale illustrating the conveyor and chain drive mechanisms.

Figure 9 is a plan view of the drive mechanism 10 of Figure 8.

Figure 10 is an end view partly in section of one type of reciprocating mechanism for effecting intermittent movement of the conveyor.

Figure 11 is a detail of the pawl mechanism of 15 Figure 10 for engaging the work carriers.

Figure 12 is a sectional view showing the middle chain supporting sprocket and its support.

Figure 13 is a sectional view of one of the elongated chain guide members also illustrating its 20 manner of support.

Figure 14 is a plan view of another type of reciprocating mechanism for effecting intermittent movement of the conveyor.

Figure 15 is a side elevation of the mechanism 25 of Figure 14 illustrating especially the conveyor chain drive.

Figure 16 is a view taken along lines 16—16 in Figure 15 illustrating further the conveyor chain drive.

Figure 19 is a view taken along line 19—19 in 30 Figure 18 further illustrating the safety device.

Figure 20 is a section taken along line 20—20 in Figure 18.

Figure 21 is a section taken along line 21—21 in 35 Figure 18.

Figure 22 is an end view, partly in section illustrating the yieldable guide section mounting.

Figure 23 is a section taken along line 23—23 of Figure 5 showing the guide section pivot.

Figure 24 is a section taken along line 24—24 of Figure 5 illustrating further the guide section support.

Figures 25a, b and c illustrate a novel blasting arrangement and method in which the blast stream is offset with respect to the rotating work.

Like reference characters are used to designate like parts.

With especial reference to Figures 1, 2 and 4 the whole apparatus is supported upon a base 11 and extending longitudinally of the base is a 55 chamber 12 containing a plurality of blasting stations and defining a region which will be hereinafter called an abrading zone. Above the chamber is supported an endless guide rail 13 from which depends a conveyor 14 bearing a plurality of work carriers 15.

For intermittently moving conveyor 14 along the guide rail a one way drive mechanism generally indicated at 16, and driven from an intermittent drive generally indicated at 17, is slidably mounted on the guide rail and adapted to position each work carrier in succession before the successive blasting stations. A continuous chain drive generally indicated at 18 in Figure 4 engages and rotates continuously the work carriers while they are in the abrading zone.

Abrading zone

Chamber 12 enclosing the abrading zone has a 75

vertical side wall 19 upon which are mounted four abrasive propelling wheel housings 21, 22, 23 and 24 which open into the interior of the chamber. Each housing includes therein an abrasive propelling wheel 25 of the type shown in Figure 7, in which a rotor 26 is provided with a plurality of substantially radial blades 27 which terminate short of the central axis about which the wheel rotates to define a central abrasive admitting space.

Rotor 26 also supports an impeller blade assembly 28 surrounded by a cylindrical hollow control member 29, provided with a discharge slot 31. Control member 29 is adjustably mounted to rotate about its axis with respect to the rotor and in this way effective directional control of the discharged abrasive is obtained. This abrasive propelling wheel per se forms no part of the present invention and is disclosed in more detail in the copending application of myself and Walter L. Keeler Serial No. 726,188, filed May 17, 1934.

As clearly shown in Figures 1 to 3 the four abrasive propelling housings define four individual blasting stations. Housing 21 is secured in any suitable manner as by bolts to a flange 20 which surrounds the blasting station opening in wall 19 and is therefore removable at will. Internally of housing 21 the rotor 26 is mounted upon an extension of shaft 32 which is driven through a suitable enclosed power transmitting unit 33 by an electric motor 34 also secured to wall 19. Housing 21 is provided with a door 35 for inspection of rotor 26, for replacement of blades 27 and housing liners and for like purposes, without entering chamber 12.

Inasmuch as each of the blasting stations are of substantially the same construction, it will be merely pointed out here that the rotors in each of the housings 22, 23 and 24 are provided with individual motor drives similar to that described for the rotor in housing 21.

Besides being spaced horizontally as shown in Figure 4, the blasting stations are stepped vertically as shown in Figures 1 and 2. Furthermore, the abrasive propelling wheels in housings 21 and 22 are preferably over shot wheels while those in housings 23 and 24 are preferably under shot wheels. Either type of wheel, however, may be used at any station as desired for the particular type of work being handled.

Thus the stepped vertical spacing of the blasting stations, the above described angular control at 29 for the abrasive discharge streams and the optional use of undershot or overshot wheels all combine to provide an abrading zone which will thoroughly subject to abrading action articles of greatly varying shapes and sizes.

In Figure 3 is diagrammatically shown the operation of the spaced blasting stations 21', 22', 23' and 24' in effectively subjecting every part of an elongated piece of work W to abrading action. Here the two lower wheels are undershot while the upper two are overshot to gain the desired abrading action.

As shown in Figure 4, chamber 12 is provided with an entry chamber 36 and an exit chamber 37. Each of these chambers is provided with a plurality of flexible self-closing doors 38 secured at opposite sides of a passage 39 and are adapted to be pushed open by the moving work as shown in Figure 4. End wall 41 of chamber 36 is provided with an elongated opening 42 which terminates in a vertical slot 43, the purpose of which will be later described.

Work moving mechanism

Although any suitable guideway may be used for supporting conveyor 14, I prefer to use a guide rail 13 shaped substantially as an I-beam rigidly secured to base 11 by supports or suspended from overhead by brackets, which are omitted for the sake of clarity in disclosing the invention. Guide rail 13 forms a closed horizontal path having a straight portion disposed above the abrading zone as shown in Figure 4.

Guide rail 13 has a central web 44 and two parallel flanges 45 and 46 extending outwardly from opposite sides of the web and serving as guide supports for two hanger wheels 47 and 48 respectively. Wheel 48 is journaled at the upper end of arm 49 which extends downwardly and inwardly and terminates in a downwardly extending portion 51 extending substantially parallel to web 44 (Figure 6).

Wheel 47 is journaled at the upper end of arm 52 similar to arm 49 and terminating in a downwardly extending portion 53 substantially parallel to web 44. A generally C-shaped hanger 54 is provided with a rigid upstanding flat plate 55 which is preferably integral with hanger 54. Plate 55 is of such thickness that it fits snugly between downwardly extending arm portions 51 and 53 and all three members 51, 53 and 55 are secured together rigidly by bolts or other suitable means. Plate 55 is preferably centered vertically with respect to web 44.

At the lower end of hanger 54 is a vertically disposed cylindrical boss 56 also centered with web 44 and in which is supported a hanger bearing shaft 57. A ball bearing has its inner race 58 secured to shaft 57 near the top of boss 56 and its outer race 59 fitted in an internal annular shoulder 61 cut in boss 56. A second ball bearing has its inner race 62 secured to shaft 57 near the bottom of boss 56 and has its outer race 63 secured in an internal annular shoulder 64 cut in the lower end of boss 56. The inner races 58 and 62 are separated by a cylindrical spacer member 65 surrounding shaft 57 and shaft 57 is provided with an enlarged portion 66 for engaging the lower end of bearing ring 62.

The upper end of shaft 57 is provided with a stub 67 of reduced cross-section and loosely mounted on this stub is a substantially cup shaped bearing collar 68 having a hub portion 69 engaging the top bearing and an external flange 71 fitting over a short cylindrical boss extension 72 of reduced cross-section. Stub 67 is threaded at the upper end and mounts a nut 73 which bears on the top of collar 68 and clamps the latter rigidly against inner bearing race 58. Running clearance is provided between exterior flange 71 of collar 68 and extension 72 of boss 56.

As shown at 75 in Figure 6, a sprocket 74 is suitably and non-rotatively secured to shaft 57 below boss 56. A locknut 76, cooperating with a threaded portion 77 on shaft 57, forces sprocket 74 upwardly against the enlarged shaft portion 66 and thereby secures the sprocket against movement axially of shaft 57. Sprocket 74 is provided with a plurality of teeth 78 the purpose of which will later be described.

Shaft 57 ends a short distance below sprocket 74. A rod 78' is suitably and non-rotatably secured to the lower end of shaft 57 by means of a removable coupling 79. Rod 78' is provided at its lower end with a hook 83 (see Figure 1) or some similar formation to which work to be abraded or cleaned is attached.

Below collar 79, rod 78' extends through a slot 80 in the top wall 88 of chamber 12. This slot and its seal below described extends throughout the chamber 12, including chambers 36 and 37. Suitable means are provided for sealing off the slot to prevent abrasive and dust from escaping therethrough. Vertically disposed walls 84 and 85 define a chamber passage extending downwardly from slot 80. Walls 84 and 85 are provided with outwardly extending foot portions 86 and 87 respectively for securing the same to under side of the top wall 88 of chamber 12. Edge plates 89 and 91 define the edge of slot 80 above wall 88. At one side of the slot, members 86, 88 and 89 are secured together as by bolts or rivets and at the other side of the slot, members 87, 88 and 91 are similarly secured.

A thin metal bracket 92 is secured to wall 84 and has an upper lip portion 93 secured to the under side of plate 89 and extending at right angles toward rod 78'. Lip 93 terminates adjacent rod 78' and clamped between lip 93 and a longitudinally extending metal strip 94 is a sheet of flexible material 95 such as felt, rubber, leather, etc. normally tending to extend horizontally. The lower end 96 of bracket 92 is bent downwardly and inwardly and terminates adjacent rod 78'. A strip of flexible material 97 normally tending to extend in alignment with bracket end 96 is secured between the bracket end 96 and a backing strip 98 by rivets 99 or some other suitable means.

A duplicate bracket 92 is secured to plate 91 and wall 85 at the other side of the slot. Flexible members 95 and 97 are of such length that they would completely close the slot were it not for the presence of rod 78'. However when rod 78' is passing along the slot these flexible strips are bent downwardly to intimately engage opposite sides of rod 78' and cooperate to provide an effective sealing means.

Hanger 54 is provided on the opposite side from boss 56 with a pair of horizontally extending apertured lugs 101 and 102. Pin 103 extends between lugs 101 and 102 respectively and is secured thereto by cotter pins 104 and 105 or the like fastening means. Guide roller 106 is journaled on pin 103 between the lugs and engages guides 109 bolted at 110 to frame member 107. Flange 108 of frame member 107 is preferably provided with slots 111 to allow horizontal adjustments of the guide 109.

Directly opposite the position where the work rotating sprockets 74 start to engage the chain 18, a short guide section 109a is adjustably and yieldably supported upon the frame member 107. One end of guide section 109a is provided with a circular aperture 236 fitting about an enlarged cylindrical portion 237 on a guide section support bolt 238. The upper end of bolt 238 cooperates with a slot 111 in the frame member 107 to allow horizontal adjustment of the guide section. Guide section 109a is rotatable about post 237 as a pivot.

Near its other end guide section 109a is supported by a second bolt 239 similar to bolt 238, but here the guide section aperture is an elongated arcuate slot 241 allowing limited rotation of guide section 109a about its pivot post 237.

At the rear of guide section 109a, and intermediate the support bolts, is provided a substantially semi-circular groove 234. A rod 231, threaded substantially along its entire length, is provided with a flat head which extends between the walls of the groove and is pivotally mounted

therein by means of pin 232. The other end of rod 231 is supported in a bushing 226 upon the upturned leg of a substantially L-shaped support 225 rigidly secured to frame 107.

Rod 231 has mounted thereon a coil spring 230 which is compressed between flanges on the bushing 226 and collar 227. Nuts 228 and 229 threaded on rod 231 abut bushing 226 and collar 227 respectively and maintain spring 230 under compression. Adjustment of nut 229 regulates the compression of spring 230. Adjustment of nut 228 changes the effective length of rod 231 and hence tends to rotate guide section 109a about its pivot 237.

It will be noted that spring 230 normally tends to maintain the guide position of guide section 109a in alignment with guide 109. However, in case a tooth of sprocket 74 should, upon engaging chain 18, contact a chain roller 220 rather than the space between adjacent rollers, the guide section 109a will yield under the pressure and pivot about post 237 against the action of spring 230. This permits the sprocket tooth to slide past the roller into the next space between the rollers without causing jamming or injury to the apparatus. After the sprocket has passed, spring 230 returns the guide section 109a to alignment with guide 109.

As shown in Figure 6, guide angles 242 and 243, forming a guide channel throughout the length of chamber 12, are provided on opposite sides of the rods 78' just above the sealed slot in wall 88. These guides prevent excessive swaying of heavy articles mounted on rods 78'. With reference to Figure 5, it will be noted that guide 242 is provided with an offset portion 235 opposite sprocket 192' to permit sidewise motion of the rod 78' when a sprocket tooth initially engages a chain roller as explained above.

The above described work carrier is connected to conveyor chain 14 in the following manner. At each work carrier an apertured link 112 embraces the work carrier and as shown in Figure 6 fits snugly in grooves 113 and 114 on opposite sides thereof. Since each link 112 has closed ends where it is pivoted to the adjoining link, conveyor chain 14 thus interconnects all of the work carriers for simultaneous movement.

A further interconnection between adjacent work carriers is shown in Figures 1 and 5. Each hanger 54 is provided with oppositely extending lugs 115 and 116 upon which are pivoted links 117. One end of each link 117 is slotted as at 118 to compensate for the outward swing of the lugs upon a curve in the guideway.

Conveyor chain 14 and the attached work carriers are moved intermittently along guide 13 by any suitable intermittent drive such as the well known pitman drive at 17 actuating a one way clutch mechanism 16. It will be apparent that other equivalent intermittent drive means such as a limit-switch and time-relay controlled electric motor can be used for the same purpose as the strictly mechanical drive above described. In fact, the use of any mechanical, electrical or hydraulic intermittent drive is well within the scope of the invention. With reference to Figures 4 and 8 to 11 a motor 119 is adjustably mounted in suitable slide guides upon a rigid frame member 121. Upon the motor shaft 122 is mounted a pulley 123 connected by a belt 124 to a pulley 125 on the shaft 126 of a speed reduction mechanism contained in housing 127.

Driven shaft 128 extending from housing 127 carries a pinion 129 which is meshed with a gear 75

131 fixed on a shaft 130 which is journaled and suspended in suitable brackets 132 and 133 affixed to the frame. Gear 131 is provided with an eccentric pin 134 engaging a slot 135 in a link 136 pivoted at one end at 137 to the frame and having a reduced extension at the other end pivotally mounted between the jaws of bifurcated member 138.

A second link consists of two aligned arms 139 and 141 having adjacent ends threadedly engaging a turnbuckle 142. Upon the other end of arm 139 bifurcated member 138 is threadedly secured and at the other end of arm 141 is threaded a block 143. All of the threaded connections at either end of arms 139 and 141 are locked by suitable nuts 144, 145, 146 and 147 as shown in Figure 9.

Block 143 is centrally bored at 148 to receive an upstanding pivot 149 secured to plate 150 at the top of clutch mechanism 16. A pair of duplicate arms 151 extend downwardly from plate 150 on opposite sides of guide 13 as shown in Figure 10. Each arm 151 has a horizontal top flange 152 rigidly secured to the bottom of plate 150, a downwardly extending vertical portion 153, a downwardly and outwardly extending portion 154, a downwardly and inwardly extending portion 155 and a short downwardly extending vertical portion at 156.

Secured rigidly to the top flange of rail 13 is a guide member 157 having a horizontal supporting guide surface 158 and two angularly disposed guide surfaces 159 and 161 on opposite sides thereof. A guide roller 162 is rotatably journaled in arm portions 153 and is supported upon surface 158. Arm portions 151 are provided with rollers 163 and 164 adapted to engage guide surfaces 159 and 161 respectively. It will therefore be seen that the frame made up of plate 150 and arms 151 is supported for movement along guide 157 by roller 162 and prevented from turning laterally thereof by guide rollers 163 and 164.

Each arm portion 156 (Fig. 11) has a pair of inwardly extending lugs 165 and 166 between which is pivoted a pawl 167. Secured to each portion 156 at one side of the pawl is a stop 168 preventing pivotal movement of the pawl in that direction and a spring 169 interconnects the pawl and stop 168 to tend to maintain the pawl normally pressed against the stop.

Secured upon the upper end of shaft 130 (Fig. 8) is a sprocket 171 which is connected by chain 172 to drive a similar sprocket 173 fixed to the upper end of shaft 174. Shaft 174 is rotatably suspended in suitable bearing brackets 175 and 176 secured to the frame and is provided with a flexible coupling portion 177 intermediate its ends. To the lower end of shaft 174 is fixed a double sprocket 178 adapted to drive the chain 18. Shaft 174 is disposed at one end of the abrading zone and midway of the abrading zone is supported rotatably a double idler sprocket 179, mounted for rotation about stub shaft 180 which has its upper end secured as by welding to a plate 181 as shown in Figure 12. Plate 181 is secured to the underside of a rigid frame portion 182 by bolts 183. Slots 184 are provided in plate 181 to enable the plate to be adjusted laterally toward and from the work carriers. Bushing 185 surrounds the lower end of shaft 180 and is rotatably mounted thereupon by suitable ball bearing members 186 and 187 spaced by a cylindrical spacing element 188. A nut 189 upon the

threaded lower end of shaft 190 maintains the bearing assembly in position.

Sprocket 179 is secured to bushing 185 by any suitable means such as screws 191. Thus, idle sprocket 179 serves as a support and guide for chain 18 to prevent excessive sagging and thus assures proper mesh of chain 18 and sprocket teeth 78.

Shaft 174 (Fig. 6), below the bearing assembly 176, is provided with an enlarged portion 196. Extending beyond enlarged shaft portion 196 is a reduced shaft portion 202 provided with a keyway 203. Sprocket 178 is provided with a keyway 204 at its inner bore and the shaft and sprocket are non-rotatably secured together by a suitable key 205 fitting in those keyways. Sprocket 178 is clamped longitudinally upon shaft portion 202 in engagement with enlarged portion 196 at its upper end. At the lower end of sprocket 178 a washer 206 is forced upwardly by a nut 207 mounted on the reduced and threaded shaft end 208 to secure the sprocket against longitudinal movement. A shaft 192 (see Figure 5) upon which is mounted a sprocket 192', is a duplicate of the shaft assembly at 174 just described except for the drive sprocket 173 and is used to support and guide chain 18 at the other end of the abrading zone.

Guide 109 prevents the work carriers from being forced away from chain 18. Suitable guide members 209 and 211 are provided to assist sprocket 179 in preventing chain 18 from being pushed too far in the opposite direction.

Guide member 209 as shown in Figure 13 is secured as by cap screws 210 to an angle member 212 which is bolted at 213 to the underside of frame member 182. Angle member 212 is provided with slots 214 and 215 to allow adjustment of guide member 209 both horizontally and vertically.

Guide member 209 is provided with two spaced bearing rails 216 and 217 adapted to engage and guide upper and lower rollers 218 and 219 respectively of chain 18. Central roller 220 of chain 18 is engaged by sprocket 174 of the work carrier. It will be noted that the chain links 221, 222, 223, 224 are not engaged by any of the sprocket members.

Since guide members 209 and 211 are duplicates the latter will not be described in detail.

Operation

Castings or any articles to be abraded or cleaned are mounted upon the work carrier hooks 83 at a station located at any portion of the apparatus outside the abrading zone and along guideway 13. Preferably this station is located at the right in Figure 1 and Figure 4, just before the entrance doorway 42 of chamber 36.

The conveyor 14 and all of the supported work carriers are intermittently moved along guideway 13 by operation of the crank 134 which causes reciprocation of the one way clutch mechanism 16 along guide 157. In its travel to the left in Figure 4 clutch mechanism 16 advances the conveyor a full step but upon return movement of clutch 16 the pawls are swung aside as shown in dotted lines in Figure 11 and do not move the conveyor.

As the conveyor moves along the guideway 13 the work enters doorway 42, see Figures 1 and 4, proceeds through the self closing doors 38 to the abrading zone 12.

The intermittent movement is so arranged that upon entry into the abrading zone the first dwell period of the work occurs adjacent and in

the blast stream from the first blasting station 21. However, the moment the work carrier enters the abrading zone, sprocket 174 is caused to engage a section of continuously moving chain 18 arranged parallel to the guide 13 at that zone. Thus the work is continuously rotated during the time it is passing through the abrading chamber.

After its dwell period at the first station, which period is timed to permit at least one complete revolution or any desired whole number of complete revolutions of the work to secure uniform abrading action, the work is moved to position before each succeeding blasting zone in order for a similar dwell period. The blast streams at the various blasting stations are preferably directed at various angles to secure more uniform and complete abrading action.

It will be seen that in the above described embodiment of my invention each piece of work is subjected in succession to four individual blasting operations before it moves into the exit chamber 37. Each separate operation accomplishes a definite abrading action and all four combine to thoroughly and uniformly subject the whole piece of work to abrading action.

Modified reciprocating mechanism

Figures 15 to 17 illustrate a modified form of reciprocating clutch mechanism which has been found very efficient in operation. In this embodiment, a substantially horizontal top plate 244 has rigidly secured thereto depending side frames 245 and 246 which extend a substantial distance below rail 13 on either side thereof. A vertical post 247 is secured as by welding to the top plate.

Secured to the top of rail 13 is a guide support 248 upon which the clutch mechanism is reciprocated. At each corner of plate 244 is secured a bracket 249 which extends beyond the edge of the plate and rotatably carries a guide wheel 251. These four wheels 251 serve to support the clutch mechanism for movement along guide 248.

Each bracket 249 also carries a rotatable guide wheel 252 which engages the lower inclined guide surfaces of guide 248 to prevent the clutch mechanism from being rotated about the rail 13.

Vertically disposed rods 253 and 254 are rotatably supported in the side frames 245 and 246 respectively. Secured non-rotatably, as by pins 255, to the lower ends of rods 253 and 254 are conveyor chain engaging arms 256 and 257 respectively. The free ends of arms 256 and 257 are preferably rounded as shown in Figure 16 for positively contacting cylindrical chain portions but it will be obvious that these arms may assume any desired shape without departing from the spirit of the invention. It will be obvious that rotation of rods 253 and 254 in opposite directions will move arms 256 and 257 to and from chain engaging positions.

As shown in Figure 15, rod 254 extends upwardly through an aperture in plate 244 and is provided with a circumferential bearing flange 258 engaging the top surface of plate 244. A flat link 259 is provided with a hollow boss 261 which fits over the top of rod 254 and is non-rotatively secured thereto as by a pin 262. Link 259 carries rotatably at its free end a second link 263 which in turn is rotatably mounted at the end of the reciprocating pull rod generally designated at 260. A similar pair of links 264 and 265 connect rod 253 to the end of the pull rod 260.

The pull rod 260 will now be described with especial reference to Figures 14 and 18 to 21. As

shown in Figures 14 and 18 the end of the pull rod to which the clutch mechanism is attached comprises a flat plate 266 having an elongated slot 267 longitudinally disposed therein. Slot 267 is adapted to receive slidably the post 247 for a purpose to be later described.

Rigidly secured to the other end of plate 266 is a tubular sleeve 268 and slidably mounted within sleeve 268 is a rod 269. Rod 269 has at its outer end an eared portion 270 adapted to engage a suitable eccentric mechanism such as the link 136 of Figure 9. Intermediate its ends rod 269 is provided with a turnbuckle 271 for adjusting the point at which the work supports will dwell in the blast chamber. The turnbuckle is held in adjusted position as by locknuts 272 and 273.

A collar 274 is rigidly and non-rotatively secured to rod 269 near the end of sleeve 268 and is provided with a beveled surface 275 for a purpose later to be described.

Supported upon the end of sleeve 268 is a safety release which is operative to prevent damage to the work moving apparatus or the article being abraded by permitting separation of the sleeve 268 and the rod 269 when the pull on the pull rod is in excess of a predetermined amount. This safety release is supported by a pair of spaced plates 271' rigidly secured as by welding to diametrically opposite sides of sleeve 268. Below and above the sleeve 268, plates 271' serve as pivots for axially extending links 276 and 277. Links 276 and 277 are provided, intermediate their ends, with inwardly extending tapered ears 278 and 279 respectively for a purpose later to be described.

A cross-bar 281 is rigidly secured to the outer end of link 277. Pivotally mounted at opposite ends of cross bar 281 and extending past opposite sides of rod 269 are a pair of threaded rods 282 and 283. These rods 282 and 283 extend through apertures in angle members 284 and 285 respectively secured to opposite sides of lower link 276.

Angle members 284 and 285 are limited in movement in one direction along the rods by suitable adjustable stops such as the nuts 286 and 287 threaded upon rods 282 and 283 respectively above the angle members. Angle members 284 and 285 are yieldably urged against these stops by coil springs 288 and 289 respectively and the tension of these springs is adjustably controlled by suitable means such as the locknut and washer assemblies indicated at 291 and 292 respectively in Figure 19.

In operation, pull rod 260 acts substantially as a solid rod with collar 274 contacting the end of sleeve 268 and the link ears 278 and 279 upon opposite drive strokes. Referring to Figure 14 it will be noted that, due to elongated slot 267, initial movement of the pull rod to the left operates through links 264, 265 and 263, 259 to rotate rods 253 and 254 and hence arms 256 and 257 in opposite directions. This movement positively insures release of chain 14 by the clutch mechanism.

As soon as arms 256 and 257 release the chain, the end of slot 267 contacts post 247 and the whole clutch mechanism is positively moved along guide 248 for the idle stroke. Movement of pull rod 260 to the right obviously causes initial movement of arms 256 and 257 to the chain engaging position shown in Figure 16 and subsequent movement of the clutch mechanism and the chain to the right.

In the event that a piece of work becomes jammed, or if for any other reason the force resisting feeding movement of the clutch mechanism becomes excessive, collar 274, due to its beveled face 275 and the tapered ears 278 and 279, will force links 276 and 277 apart against the action of springs 288 and 289 and thus allow separation of sleeve 268 and rod 269 without damaging the apparatus. The several adjustments on rods 282 and 283 allow this separation to take place at a desired predetermined stress.

It will be obvious that the pull rod shown in Figure 9 may be used with the clutch mechanism of Figures 14 to 17 and the pull rod of Figures 18 to 21 may be used in place of that of Figure 9 since these parts are unitary and interchangeable.

Method of offset blasting

In Figures 25a, 25b and 25c I have illustrated the advantages of my novel method of abrading rotating articles in securing thorough abrasive action. Figure 25a represents one system of directing a blast stream centrally of the axis of rotation of the work. Here the work is just about to complete a 360 degree rotation in the blast stream and, as indicated by the zig zag line, portions A to C and B to D on the inside of the work have not been subjected to abrasive action due to the cut-off effected by the edges at A and B.

In my arrangement for cleaning substantially circular articles of this type such as cylinder blocks and other automotive castings I preferably position the blast streams from the first two blasting stations slightly offset to the left with respect to the centers of rotation of the work before those stations. Figure 25b shows the work just before it has completed a full revolution at the station and it will be noted that all portions except the areas B to E have been cleaned.

Figure 25c illustrates the same piece of work near the end of a complete revolution before each of the third and fourth blasting stations. Here the blast stream is offset slightly to the right with respect to the center of rotation of the work and all parts of the work are subjected to abrasive action except the area A to F. However, area A to F was cleaned at the first two stations as shown in Figure 25b and it will thus be seen that the combined action of all four blasting stations thoroughly cleans the entire work surface inside and out.

In carrying out the above described method the blast streams must be adjusted to give such a vertical spread of abrasive as to insure cleaning of the work from top to bottom and therefore it will be seen that the method is best effective upon short pieces of work rather than the longer pieces as illustrated in Figure 3.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. In an abrading apparatus for blasting articles of relatively large size, a support, means pro-

viding an abrading zone, means for intermittently advancing a plurality of articles in sequence through said zone, comprising an endless substantially horizontal guideway on said support above said abrading zone and a plurality of individual article carriers movably supported from said guideway and adapted to be moved therewith; means to suspend said articles from said carriers; clutch means slidably mounted on said guideway, and drive means for reciprocating said clutch means along said guideway, said clutch means being operable to drivingly engage and propel said carriers in one direction of motion, whereby said articles are intermittently advanced through said abrading zone.

2. The abrading apparatus defined in claim 1, said clutch means comprising pivoted pawl mechanism engageable with said article carriers.

3. In the art of cleaning articles such as articles having relatively deep cavities therein by abrading, the steps which include moving an article along a predetermined path of travel and halting it in position before a blasting station, establishing a blasting stream at said blasting station with an impingement pattern elongated in a vertical plane, rotating said article through at least one complete revolution about an axis offset in the direction of work travel of said article with respect to the approximate vertical axis of the blast stream from said station, moving said article to a second blasting station and halting it, establishing a second blasting stream at said second blasting station with an impingement pattern elongated in a vertical plane, and rotating said article at least one complete revolution about an axis offset with respect to the approximate longitudinal axis of the blast stream from said second station, said last named offset being in a direction opposite to said first named offset, said blast streams having different directions relative to the direction of rotation of said article.

4. In an abrading apparatus, a support; means providing an abrading zone; means for intermittently moving articles through said zone comprising a guide; a plurality of article carriers movably mounted on said guide; a member mounted to reciprocate along said guide drivingly engaging an article carrier in one direction of motion only; means pivoted at one end to said member and at its other end to a slotted lever pivotally mounted on a fixed pivot; an eccentric member engaging said slotted lever; drive means for said eccentric member; means for varying the speed of said drive means; and means for adjusting the effective length of said link, for adjustably varying the point where said carriers will stop in said abrading zone.

5. In an abrading apparatus, a support; means providing an abrading zone adjacent said support; means for intermittently moving articles through said zone comprising a guide structure upon which a plurality of article carriers are movably mounted; a member mounted to reciprocate along said guide structure and operable to drivingly engage an article carrier in one direction of motion only; a link pivoted at one end to said member and at its other end to a lever, said lever being journaled on a fixed pivot; and crank

means for reciprocating said lever; means for rotating said crank means, said crank means and said lever being so related that said member is reciprocated at a greater speed in said one direction of motion than in the opposite direction of motion, whereby the time of dwell of said articles is greater than the time required to advance the articles into blasting position.

6. In an abrading apparatus, a blasting zone; a conveyor mechanism including a plurality of carriers for conveying a plurality of work units in a substantially horizontal fixed path of travel in sequence through said blasting zone; said carriers being spaced apart on said conveying means a predetermined distance from each other; a plurality of blast means disposed in said blasting zone and spaced apart along said path of travel of said work units and at the same side of said path of travel for providing a plurality of spaced blast stations in said blasting zone; means for intermittently advancing said carriers step by step a distance substantially equal to the spacing of said carriers from each other, and for stopping one of said carriers in each of said blast stations, whereby said carriers are caused to dwell and said work units are subjected to the action of said blast means for a predetermined length of time; means for rotating said carriers at least while they are disposed at said blast stations, each of said blast means embodying means for projecting abrasive at high velocity across the path of travel of said work units, one of said blast means being disposed to project its blast stream offset a slight distance rearwardly of the axis of rotation of the work unit being treated when halted with respect to the direction of advance of said work units, and another of said blast means being disposed to project its blast stream offset a slight distance forwardly of the axis of rotation of the work unit being treated when halted with respect to the direction of advance of said work units.

7. In the art of cleaning articles by abrading, the steps which include suspending an irregular shaped article in depending relationship, conveying said article to an abrading station, halting the article at said abrading station, rotating the article about a substantially vertical axis through at least one complete revolution while subjecting it to the abrading action of a stream of abrasive particles projected at high velocity in a direction substantially normal to a plane passing through said vertical axis of rotation of said article, and in a direction offset relative to said vertical axis of rotation of said article, then advancing said article to a second abrading station, halting the article in said second abrading station, and rotating the article through at least one complete revolution while subjecting the article to the action of a second stream of abrasive projected at high velocity in a direction substantially normal to a plane passing through said vertical axis of rotation of said article and in a direction offset relative to said vertical axis of rotation of said article, said last-named offset being in a direction opposite to said first-named offset.

WM. A. ROSENBERGER.
